UNITED STATES PATENT OFFICE.

JOHN S. KLEIN, OF OIL CITY, PENNSYLVANIA.

SPEED-REGULATOR FOR EXPLOSIVE-ENGINES.

SPECIFICATION forming part of Letters Patent No. 697,409, dated April 8, 1902.

Application filed May 3, 1901. Serial No. 58,636. (No model.)

To all whom it may concern:

Be it known that I, JOHN S. KLEIN, a citizen of the United States, residing at Oil City, in the county of Venango and State of Pennsylvania, have invented certain new and useful Improvements in Mechanism Compressing Gases; and I do hereby declare the following to be a full, clear, and exact description of the invention, such as will enable others skilled in the art to which it appertains to make and use the same.

This invention relates to mechanisms compressing gases; and it consists in certain improvements in the construction thereof, as will be hereinafter fully described, and pointed out in the claims.

The objects of the invention, stated generally, are to provide means whereby said mechanisms may be more economically operated than heretofore. Broadly stated, this is accomplished by giving a full opening to the valve mechanism during the initial part of a stroke, taking in gas and closing said valve mechanism when a sufficient volume of gas has been admitted to the cylinder.

The invention is peculiarly applicable to gas-engines which compress the gases forming the motive power prior to igniting them. In its broader scope, however, it includes ordinary compressors and forms when applied to them both a controlling and a relief or unloading device.

The invention is illustrated in the accompanying drawings as follows:

35 Figure 1 shows a gas-engine with the mechanism forming my invention thereon. Fig. 2 shows a compressor with the mechanism forming my invention thereon.

In Fig. 1, A marks the cylinder; A', the water-jacket; B, the piston; C, the intake-port. These are of the usual construction. The intake-valve D is arranged to move to and from its seat by a movement in the direction of the flow of gases opening in the direction of the inflow of gases. Immediately under the valve D is a chamber F. The air-port f and gas-port f' communicate with this chamber. The valves E and E' control these ports and the relative proportions of gas and air admitted.

50 The valves E and E' are arranged on the stem d of the valve D. Beneath the mixing-chamber F is a motor-cylinder G. The upper end

of this cylinder communicates through the passage g with the atmosphere. Arranged in this cylinder is a piston H. This piston is 55 connected with the valve-stem d by any convenient mechanism. Extending through the stem d is the passage d'. This passage is closed against the outflow of gas from the cylinder by means of a check-valve d'. The 60 lower end of the cylinder G is in communication with the atmosphere through a passage g', and this passage is controlled by a valve I. The valve I has the stem i' arranged to be moved in the guide g'. A spring i holds it 65 normally to its seat. The ports g' pass from the lower end of the cylinder G, and a check-valve J is arranged over these ports. A spring j holds this check-valve normally to its seat. The operation of this mechanism is 70 as follows: At the beginning of the intake-stroke of the piston the valve I is drawn from its seat. The passage g' is somewhat larger than the passage d', so that air at practically atmospheric pressure is maintained under 75 and above the piston H during the time the valve I is off its seat. This balances the piston H. The reduction of pressure in the cylinder incident to the intake movement of the piston unbalances the pressure at the opposite 80 side of the valve D, and this opens the valve D. A small amount of air passes through the passage d'; but the greater volume enters from the chamber F. The valves E and E' uncover the ports f and f' with the upward move- 85 ment of the valve D. The valve is maintained in this upward position by the forces made active by the reduced pressure in the cylinder so long as the valve I is kept from its seat. Immediately the valve I is returned to 90 its seat the pressure in the lower end of the cylinder G is reduced to that in the cylinder A. This being somewhat less than atmospheric pressure, the pressure of the air on top of the piston H forces it down, closing the valve 95 D. Thus the piston H and cylinder G form a motor for actuating the valve. Looking at this in another light, the pressure on the under side of the piston H and upper side of the valve D is practically the same, and the pressure on top of the piston H and under side of the valve D is practically the same, so that the closing pressures where the piston and valve D are of equal size would be balanced,

in which case the gravity or the spring h would close the valve. Preferably the piston II is made slightly larger than the valve in order that this action may be positive and practically instantaneous. Should it be desired that a volume of gas should be taken in with the intake-stroke equal to the full capacity of the cylinder—that is, should it be desired to have the inflow of gas continue throughout the intake-stroke—some means should be provided for permitting the closing of the valve should the valve I be brought to its seat just at the moment of the reversal of the piston. The check-valve J forms this means. It will readily be seen that should the reversal take place, so as to create a back pressure on the valve D and on the gases on the under side of the piston II, the valve J will readily open, so as to keep the pressure of gas under the piston II practically equal to the air-pressure, so that the piston may be balanced, and of course the back pressure on the valve D will balance the pressure under the valve D, so that the valve will instantly close at the end of the stroke whether the valve I is brought to its seat or not. I prefer that the connection between the cylinder and the under side of the motor be through the valve, as it makes a more convenient arrangement of mechanism; but it would be readily operated through a by-pass, as shown by a pipe d^3 , (see dotted line,) the pipe d^3 being provided with a check-valve d^4 .

In controlling gas-engines two leading methods are in vogue—one, known as the "hit-and-miss" system, wherein gas is admitted only a sufficient number of strokes to give the desired power, the admission of all the gas admitted each time being substantially the same. In the other system, known as the "throttling" system, gas is admitted at each stroke, but in varying volume. With the throttling system there is great loss of power, by reason of the fact that the intake-passages are reduced in order to decrease the volume admitted to the cylinder, so that the intake-pressure in the cylinder is very much reduced below that of the atmosphere, with work incident thereto, and this condition exists practically up to the end of the stroke of the piston and may continue with some constructions during a part of the return stroke—that is, to a point where the pressure in the cylinder will equal atmospheric pressure or the pressure of the supply-gases. With my invention a full initial opening is given to the valve, so that the initial intake-pressure in the cylinder is but little below atmospheric pressure. Thus the supply of gas is taken into the cylinder with but little work. As soon as a sufficient volume is admitted to the cylinder the intake-passage is entirely closed. From this point to the end of the stroke of the piston there is of course an opposing force, increasing as the pressure decreases in the cylinder toward the extreme end of the stroke. This work, however, is compensated for on

the return stroke of the piston, so that the piston returns to the point of cut-off without any loss except the frictional losses. This mode of operation of course is much more efficient than the ordinary throttling type of gas-engine. In addition to the saving in power in the valve mechanism of the ordinary throttling type, where they are not closed until the return movement of the piston, and consequently by the increase of pressure in the cylinder, there is apt to be a very severe shock when closed, and this acting constantly on the valves makes it difficult to keep them in proper running order. With my construction the closing of the valve while positive is not attended by any shock, and consequently with mechanism so constructed the valves will continue in proper working order for a long period of time. If desired, the opening and closing of the valve I may be controlled so as to open only a sufficient number of strokes to give to the engine its desired power—that is, to make the engine operate on the hit-and-miss principle. Of course when the valve I is not opened the valve D will not be opened and the work performed by atmospheric pressure on the piston during the return of the piston will equal the work required to move it to its outer position against the air-pressure, so that the only losses for the stroke will be the frictional losses. I prefer, however, where close regulation of speed is required to open the valve I with each working stroke of the piston, varying the power by varying the volume, as a more even operation of the engine is thus accomplished.

In order to control automatically the point of cut-off of the valve D, I have provided a mechanism for automatically controlling the closing of the valve I, as follows: Extending from the stem i^1 of the valve I is a pitman K, having a turned end k . This turned end k rides on a cam L. The cam L has the cam portion l , which when in engagement with the turned portion k moves the pitman K so as to carry the valve I from its seat. As the point l^1 of the cam L reaches the end of the turned portion k the spring i moves the valve back to its seat, the portion l^2 of the cam being sufficiently small in the center to permit of the perfect seating of the valve. The cam L is fixed on a shaft M. Also fixed on this shaft is a worm-gear N. The worm-gear N meshes a worm O. The worm O is carried by the governor-stem P. The governor Q, which may be of any ordinary type, as shown, consists of the centrifugal weights q and the centripetal element formed by the spring q^1 . Extending from the weight are the bell-crank levers q^2 , and these are connected by the link q^6 with the stem P. The weights q are carried by a rotating carrier q^3 . This carrier is mounted in an arm A^2 , extending from the cylinder. A gear q^4 is fixed on the lower end of the carrier, and a gear q^5 meshes this gear. Any suitable means of driving the gear q^4 may be provided. The speed of the stem P is such,

however, as, acting through the worm O and worm-gear N, will give to the cam L the proper rotation to open the valve with each intake-stroke of the engine. The governor 5 acting on the stem P raises and lowers the worm O in its action, and the worm O acting as a rack on the worm-gear in addition to giving to the cam its rotative motion shifts the relative position of the point l' , and consequently varies the point of cut-off of the valve D through the variation in the time of closing the valve I. Thus if the speed of the engine is too great the weights q move outwardly. This raises the stem P, and the 15 worm O, acting on the worm-gear N, rotates the cam L toward the right or in advance, and consequently makes the point l' reach the end of the turn k sooner in the point of movement of the piston than it otherwise 20 would. Thus the volume of gas taken in by this stroke is made less than the preceding stroke. If the engine is slowed down, a reverse action of the parts takes place.

This device is applicable in its broader 25 scope, as before stated, to compressors, and where so applied operates as a controlling device and a relief device. In Fig. 2 I have shown it so applied. In this figure the same letters apply to similar parts as in Fig. 1. The operation of the device is practically the 30 same, except, of course, the valve I in the normal operation of the device is moved from its seat with each intake-stroke of the compressor. Where a sufficient volume of gas 35 or air has been accumulated in the receiver, so that it is desirable to throw the compressor out of action, the worm O, operating upon the worm-gear N, (not shown in Fig. 2,) so turns the cam L as to prevent the opening of the valve I during the intake-stroke of the 40 compressor. Where this condition occurs, the device acts as a relief device, because the work necessary to carry the piston throughout the intake-stroke, where the valve is closed, 45 so that no inflow of gas or air takes place, is compensated by the pressure on the piston on the return stroke. Where a part of the capacity of the compressor is desired, the intake is cut off at some intermediate point, 50 giving to the compressor a sufficient volume for the required supply, and from the point of cut-off moves to the extreme end of the piston and back to the point of cut-off. No work is performed, and the only losses are 55 the frictional losses.

Instead of the ordinary governors as applied to gas-engines a pressure-regulator R is applied to the stem P. This consists of the chamber R', in which is the diaphragm or 60 moving element of the regulator r. Extending from the diaphragm r is a stem r'. This acts upon a lever r^2 , pivoted on an arm r^3 , which arm extends from the chamber R'. A spring r^4 is opposed to the pressure in the 65 regulator, and a screw r^5 is arranged to vary the tension of this spring. A connection r^6 is made with the receiver, so that the dia-

phragm r is subjected to the receiver-pressure. The lever r^2 connects the stem P through a spool p. This stem P is rotated by 70 any suitable mechanism, the gears p' and p^2 being shown for this purpose.

What I claim as new is—

1. In a mechanism compressing gases, the combination with the cylinder and compressing-piston therein; of a valve device arranged to control the period of admission of gases; means for opening and closing said valve device, said means being subjected to the reduction of pressure incident to the suction-stroke 75 of the compressing-piston and an opposing pressure; and mechanism controlling the application of the pressure so reduced by the suction movement of the piston to open and close the valve.

2. In a mechanism compressing gases, the combination with a cylinder and compressing-piston therein; of a valve device controlling the period of admission of gases and for preventing an outflow of gas through the intake; 80 and a fluid-actuated mechanism for closing said valve device during the intake movement of the piston.

3. In a mechanism compressing gases, the combination with the cylinder and compressing-piston therein; of a valve device controlling the period of admission of the gases and for preventing an outflow of gases through the intake; means for closing said valve device, 95 said means being subjected to the reduction of pressure incident to the suction-stroke of the compressing-piston and an opposing pressure; and mechanism controlling the application of the pressure so reduced by the suction movement of the piston to close the valve. 100 105

4. In a mechanism compressing gases, the combination with a cylinder and a compressing-piston therein; of a valve device controlling the period of admission of gases to the cylinder; a fluid-actuated motor connected with 110 said valve device; means for balancing the pressure on the moving element of the motor during the inflow of gases and for giving a preponderance of pressure to the closing side of the moving element of the motor to close 115 the valve device.

5. In a mechanism compressing gases, the combination with a cylinder and compressing-piston therein; of a valve device controlling the period of admission of gases; a fluid-actuated motor for actuating said valve device; 120 and means for subjecting one side of the moving element of the motor to the reduced pressure in the cylinder incident to the intake movement of the piston for closing the valve 125 device.

6. In a mechanism compressing gases, the combination with a cylinder and a compressing-piston therein; of a valve device controlling the period of admission of gases thereto; 130 a fluid-actuated motor for operating said valve device; means for subjecting both sides of the moving element of the motor to atmospheric pressure during the inflow of gases

and for subjecting one side of the moving element of the motor to the reduced pressure of the cylinder incident to the intake movement of the piston to close the valve device.

- 5 7. In a mechanism compressing gases, the combination with a cylinder and compressing-piston therein; of a valve device for controlling the inflow of gases; a fluid-actuated motor for operating said valve device; means for 10 subjecting the side of the moving element of the motor opposed to the closing movement of the valve to a balancing pressure during the inflow of gases; a valve mechanism for cutting off the supply of the fluid further 15 furnishing the balance of pressure; means for subjecting the side of the moving element of the motor opposed to the closing movement of the valve device to the reduced pressure in the cylinder incident to the intake movement 20 of the piston for closing said valve.
8. In a mechanism compressing gases, the combination with a cylinder and compressing-piston therein; of a valve device controlling the period of admission of gases, said valve 25 device being arranged to open in the direction of the movement of the inflowing gases; and a fluid-actuated mechanism for closing said valve device previously to the completing of the intake-stroke of the piston.
- 30 9. In a mechanism compressing gases, the combination with a cylinder and compressing-piston therein; of a valve device controlling the period of admission of gases to the cylinder; a fluid-actuated motor connected with 35 said valve device; means for balancing the pressure on the moving element of the motor with an inflow of gases and for giving a preponderance of pressure to the closing side of the moving element of the motor to close the 40 valve device; and means for changing said pressures on the moving element of the motor to close the valve before the completion of the intake-stroke of the piston.
10. In a mechanism compressing gases, the 45 combination with a cylinder and compressing-piston therein; of a valve device for controlling the period of admission of gases; a fluid-actuated motor for actuating said valve device; means for subjecting one side of the 50 moving element of the motor to the reduced pressure incident to the intake movement of the piston for closing the valve device; and a mechanism for making said means active before the completion of the intake-stroke of the piston.
- 55 11. In a mechanism compressing gases, the combination with a cylinder and compressing-piston therein; of a valve device for controlling the period of admission of gases thereto; a fluid-actuated motor for operating said valve device; means for subjecting both sides of the moving element of the motor to atmospheric pressure during the inflow of gases and for subjecting one side of the moving element of the motor to the reduced pressure of the cylinder incident to the intake movement of the piston for closing the valve de-

vice; and means for effecting a change in pressure on the moving element of the motor to close the valve device before the completion of the intake movement of the piston.

12. In a mechanism compressing gases, the combination with a cylinder and compressing-piston therein; of a valve device arranged to control the period of admission of gases and for preventing an outflow of gas through the intake; means for closing said valve device, said means being subjected to the reduction of pressure incident to the suction movement of the compressing-piston and an opposing pressure; and mechanism controlling the application of the pressure so reduced by the suction movement of the piston to close the valve device during the suction movement of the piston.

13. In a mechanism compressing gases, the combination with a cylinder and compressing-piston therein; of a valve device for controlling the period of admission of gases, said valve device being arranged to open in the direction of movement of the inflow-gases; means for closing said valve device, said means being subjected to the reduction of pressure incident to the suction movement of the compressing-piston and an opposing pressure; and mechanism controlling the application of the pressure so reduced by the suction movement of the piston to open and close the valve.

14. In a mechanism compressing gases, the combination with a cylinder and compressing-piston therein; of a valve device for controlling the period of admission of gases to the cylinder, said valve device being arranged to open in the direction of movement of the inflow of gas; a fluid-actuated motor connected with said valve device; means for balancing the pressure of the moving element of the motor during the inflow of gases and for giving a preponderance of pressure to the closing side of the moving element of the motor to close the valve device.

15. In a mechanism compressing gases, the combination with a cylinder and compressing-piston therein; of a valve device controlling the inflow of gases, said valve device being arranged to open in the direction of the movement of the inflowing gas; a fluid-actuated motor for actuating said valve device; and means for subjecting one side of the moving element of the motor to the reduced pressure in the cylinder incident to the intake movement of the piston for closing the valve device.

16. In a mechanism compressing gases, the combination with a cylinder and compressing-piston therein; of a valve for controlling the inflow of gases, said valve device being arranged to open in the direction of movement of the inflowing gas; a fluid-actuated motor for operating said valve device; and means for subjecting both sides of the moving element of the motor to atmospheric pressure during the inflow of gases, and for subjecting one

side of the moving element of the motor to the reduced pressure of the cylinder incident to the intake movement of the cylinder to close the valve device.

5 17. In a mechanism compressing gases, the combination with a cylinder and compressing-piston therein; of a valve device controlling the inflow of gases, said valve device being arranged to open in the direction of movement of the inflowing gas; a motor for actuating said valve device; means for subjecting the moving element of the motor to a reduced pressure of the cylinder; a valve for cutting off the supply of fluid furnishing the balance 15 in pressure; means for subjecting one side of the moving element of the motor opposed to the closing movement of the valve to the reduced pressure of the cylinder incident to the intake movement of the piston for closing said 20 valve.

18. In a mechanism compressing gases, the combination with a cylinder and compressing-piston therein; a valve device controlling the inflow of gases; a fluid-actuated motor for 25 operating said valve device; a connection through the valve between the cylinder and the side of the motor opposing the closing movement of the valve.

19. In a mechanism compressing gases, the combination with a cylinder and compressing-piston therein; of a valve device controlling the inflow of gases; a fluid-actuated motor for operating said valve device; a connection through the valve between the cylinder and the side of the motor opposing the closing movement of the valve; a passage leading from the side of the motor opposing the closing of the valve to the atmosphere; a valve device for controlling said passage; and means 40 for actuating said valve to close said passage during the intake movement of the piston.

20. In a mechanism compressing gases, the combination with a cylinder and compressing-piston therein; of a valve device controlling the period of admission of gases; a fluid-actuated motor for operating said valve device; a connection between the cylinder and that side of the motor opposing the closing of the valve device; and a check-valve in said connection preventing the flow of gas from the cylinder to the side of the motor opposing the closing of the valve device.

21. In a mechanism compressing gases, the combination with a cylinder and compressing-piston therein; of a valve device controlling the inflow of gases; a motor controlling said valve device; a passage leading from the side of the motor opposing the closing of the valve to the atmosphere; a check-valve in said passage opposing the passage from the atmosphere to said motor but permitting a passage of gas from said motor.

22. In a mechanism compressing gases, the combination with a cylinder and compressing-piston therein; of a valve device controlling the inflow of gases; a fluid-actuated motor for operating said valve device; a connection

between the cylinder and that side of the motor opposing the closing of the valve device; a check-valve in said passage preventing a return of gas from the cylinder to said motor; a passage leading from said side of said motor to the atmosphere; a check-valve closing said passage and preventing a flow of air to said motor, but permitting a movement 75 of air from said motor; a second passage from said side of said motor; and a valve controlling said passage.

23. In a mechanism compressing gases, the combination of the cylinder, A; the piston, B; 80 inlet-passage, C; the valve, D, arranged in said passage; the stem, d, on said valve, having the passage, d², therethrough; the cylinder, G, having the passages, g, g' and g³, to the atmosphere; the piston, H, arranged in 85 said cylinder and secured to the stem, d²; the seat-valve, d', in the passage, d²; a check-valve, J, arranged over the passage, g³; and the valve, I, arranged in the passage, g'.

24. In a mechanism compressing gases, the combination of the cylinder and compressing-piston therein; of a valve device controlling the period of admission of gases; means for closing said valve device, said means being subjected to the reduction of pressure incident to the suction movement of the compressing-piston, and an opposing pressure; and mechanism for controlling the application of the pressure so reduced to effect the action of said means at different points in the 100 suction-stroke of the piston to vary the volume of gas compressed by the return stroke of the piston.

25. In a mechanism compressing gases, the combination with a cylinder and compressing-piston therein; of a valve device controlling the period of admission of gases; means for opening and closing said valve device, said means being subjected to the reduction of pressure incident to the suction movement of the compressing-piston, and an opposing pressure; and mechanism controlling the application of the pressure so reduced for effecting an action of said means to open the valve during the initial movement of the piston and to close said valve at different points in the suction-stroke of the piston to vary the volume of gas compressed by the return stroke of the piston.

26. In a mechanism compressing gases, the combination with a cylinder and compressing-piston therein; of a valve device for controlling the period of admission of gases and for preventing an outflow of the gases through the intake; a fluid-actuated mechanism for closing said valve device at different points in the intake-stroke of the piston to vary the volume of gases compressed by the return stroke of the piston.

27. In a mechanism compressing gases, the combination with a cylinder and compressing-piston therein; of a valve device controlling the inflow of gases to the cylinder; a fluid-actuated motor connected with said valve de-

vice; means for balancing the pressure on the moving element of the motor during an inflow of gas and for giving a preponderance of pressure to the closing side of the moving element of the motor to close the valve device; and means for varying the moment of the change in pressure on the respective sides of the moving element of the motor to vary the point in the intake-stroke at which the valve device is closed.

28. In a mechanism compressing gases, the combination with a cylinder and compressing mechanism therein; of a valve device controlling the inflow of gases therein; a fluid-actuated motor for operating said valve device; means for subjecting both sides of the moving element of the motor to atmospheric pressure during an inflow of gases and for subjecting one side of the moving element of the motor to the pressure of the cylinder incident to the intake movement of the piston for closing the valve device; and means for varying the moment of subjecting the one side of the moving element of the motor to the reduced pressure to vary the point in the intake-stroke at which the valve device is closed.

29. In a mechanism compressing gases, the combination with a cylinder and compressing-piston therein; of a valve device for controlling the inflow of gases; a fluid-actuated motor for operating said valve device; means for subjecting the moving element of the motor opposed to the closing movement of the valve to a balancing pressure during an inflow of gases; a valve mechanism for cutting off the supply of fluid furnishing the balance of pressure; and means for subjecting the side of the moving element of the motor opposed to the closing movement of the valve device to the reduced pressure in the cylinder incident to the intake movement of the piston for closing said valve; and means for actuating said valve mechanism to vary the point of cutting off the supply of fluid furnishing the balance of pressure to vary the point in the intake movement of the piston at which the valve device is closed.

30. In a mechanism compressing gases, the combination with a cylinder and compressing-piston therein; of a valve device, controlling the inflow of gases; a fluid-actuated motor for actuating said valve device; a connection between the side of the motor opposing the closing movement of said valve device and the cylinder; a passage from said side of the motor to the atmosphere; a valve controlling said passage; and means for actuating said valve at various points in the intake-stroke to vary the volume of gas admitted.

31. In a mechanism compressing gases, the combination with a cylinder and compressing-piston therein; of a valve device controlling the period of admission of gases; means for closing the said valve device, said means being subjected to the reduction of pressure incident to the suction movement of the compressing-piston and an opposing pressure;

mechanism for controlling the application of the pressure so reduced to effect the closing of said valve device at various points in the suction-stroke of the piston; and a governor for controlling at the point at which said mechanism acts.

32. In a mechanism compressing gases, the combination with a cylinder and compressing-piston therein; of a valve device for controlling the period of admission of gases and for preventing an outflow of gases through the intake; a fluid-actuated mechanism for closing said valve device at different points in the intake-stroke of the piston; and a governor for controlling the point at which the said closing mechanism is made active.

33. In a mechanism compressing gases, the combination with a cylinder and compressing-piston therein; of a valve device controlling the period of admission of gases thereto; a fluid-actuated motor for operating said valve device; means for subjecting both sides of the moving element of the motor to atmospheric pressure during the inflow of gases and for subjecting one side of the moving element of the motor to the reduced pressure of the cylinder incident to the intake movement of the piston for closing the valve device; and a governor controlling the moment at which the one side of the motor is subjected to the cylinder-pressure to vary the moment of closing the valve device.

34. In a mechanism for compressing gases, the combination with a cylinder and compressing-piston therein; a valve device for controlling the inflow of gases thereto; a fluid-actuated motor for operating said valve device; means for subjecting the side of the moving element of the motor opposed to the closing moment of the valve to a balancing-pressure during the inflow of gases; a valve mechanism for cutting off the supply of fluid furnishing the balance of pressure; means for subjecting the side of the moving element of the motor opposed to the closing movement of the valve device to the reduced pressure in the cylinder incident to the intake of the piston for closing said valve; and a governor for controlling the moment at which the said element of the motor is subjected to the pressure from the cylinder.

35. In a mechanism compressing gases, the combination with a cylinder and compressing-piston therein; of a valve device for controlling the inflow of gases therein; a motor connected with said valve device; a connection between the cylinder and that side of the motor opposed to the closing of the valve device; a passage from said side of the motor to the atmosphere; a valve controlling said passage; and a governor controlling said valve.

36. In a mechanism for compressing gases, the combination with a cylinder, A, and compressing-piston therein; of a valve, D, controlling the inflow of gases thereto; a cylinder, G; a connection between the cylinder, G, and the cylinder, A; a check-valve in said

connection; the piston, H, said piston being subjected to atmospheric pressure on the side toward the valve, D; the passage, g' ; a valve, I, controlling said passage; and a governor 5 controlling the valve, I.

37. In a mechanism compressing gases, the combination with a cylinder, A, and compressing-piston therein; of a valve, D, controlling the inflow of gases thereto; a cylinder, G; a connection between the cylinder, G and the cylinder, A; a check-valve in said connection; the piston, H, said piston being subjected to atmospheric pressure on the side toward the valve, D; the passage, g' ; a valve, I controlling said passage; and a governor mechanism controlling the valve, I, to open said valve during the initial movement of the piston and to close said valve at various points in the intake movement of the piston.

38. A governor comprising a reciprocating and rotating stem acting with the controlling element of the governor mechanism; a worm on said stem; a gear meshing said worm; a valve device, and means driven with said gear for controlling a valve device.

39. A governor comprising a reciprocating and rotating stem acting with the controlling element of the governor mechanism; a worm on said stem; a gear meshing said worm; a cam driven by said gear; and a valve device operated by the rotative movement of said cam incident to the rotating movement of the worm, the action of the valve device being varied by a variation in the position of the cam 35 due to an axial movement of said worm.

40. In a mechanism compressing gases, the combination with a cylinder and compressing-piston therein; a valve device controlling the inflow of gases; a governor mechanism comprising the worm, O, gear, N, cam, L, having the cam-surface, l , and shoulder, l' ; means operated by said cam for making active said valve device, said cam being arranged to effect the closing of said valve device during 45 the intake movement of the piston and to vary the moment of closing by a relative variation in the position of the shoulder, l' .

41. In a mechanism compressing gases, the combination of a cylinder and compressing-piston therein; a valve device controlling the inflow of gases therein; a fluid-actuated motor for operating said valve; the valve, I, for controlling said motor; a cam, L, for controlling the valve, I; a worm-gear operating with 55 said cam; a worm having a rotative and axial movement operating with the controlling element of the governor meshing said gear, and a governor.

42. In a mechanism compressing gases, the

combination of the cylinder, A; the valve, D, 60 controlling the inflow of gases therein; a cylinder, G; a connection between the cylinder, G, and the cylinder, A; the valve, I, controlling the inlet of the cylinder, G; the cam, L; means for communicating movement from 65 the cam, L, to the valve, I; a worm-gear operating with said cam; a worm meshing said gear; a governor; means actuated with the controlling element of the governor for reciprocating said worm; and means for giving 70 said worm rotative movement.

43. In a gas-engine, the combination of a cylinder; the valve, D, controlling the period of admission of gases; the air and gas valve carried with said valve; a motor operating 75 upon said valve; and a connection between the side of the motor opposed to the closing of the valve, D, and the cylinder.

44. In a gas-engine, the combination of a cylinder; the valve, D; the air and gas valve 80 carried with said valve; a motor operating upon said valve; a connection between the side of the motor opposed to the closing of the valve, D, and the cylinder; a passage leading from the said side of said motor to the atmosphere; a valve, I, controlling said passage; and means for closing said valve during an intake-stroke of the engine.

45. In a gas-engine, the combination of a cylinder; the valve, D; the air and gas valve 90 carried with said valve; a motor operating upon said valve; a connection between the side of the motor opposed to the closing of the valve, D, and the cylinder; a passage leading from the said side of said motor to the atmosphere; a valve, I, controlling said passage; means for closing said valve, I, during an intake-stroke of the engine; and a governor for controlling the moment of the closing of the valve, I.

46. In a gas-engine, the combination with the cylinder, A; the valve, D, controlling the inflow of gases thereto; the stem, d, extending therefrom; a passage, d^2 , through said stem; a check-valve, d' , in said passage; the air and gas valves, E and E', arranged on said stem; the cylinder, G, having the passage, g , g' and g^3 ; the piston, H, arranged in the cylinder, G; the check-valve, J, on the passage, g^3 ; the valve, I, in the passage, g' ; and a governor mechanism controlling the valve, I.

In testimony whereof I affix my signature in presence of two witnesses.

JOHN S. KLEIN.
